UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. **6,836**, dated September 2, 1873; application filed August 9, 1873.
[Term of Patent 3½ years.]

To all whom it may concern:

Be it known that I, FREDERICK WINK, of the city and county of Philadelphia, State of Pennsylvania, have invented a Design for Shawl-Pattern, of which the following is a specification:

My design for a striped shawl-pattern is sufficiently illustrated by the figure in the accompanying drawing, the remainder being merely a repetition of that which appears.

The whole pattern is composed of a series of parallel plain stripes, of different widths and shades or colors; or it may be considered as composed of two main members or stripes,

A and B, of which the points *x* and *y* are the centers, and *z* the division-line.

Irrespective of the colors employed, I claim—

The design for a shawl-pattern, as described, and as illustrated in and by the accompanying drawing.

In testimony whereof I have signed my name to this specification in the presence of two subscribing witnesses.

FRED. WINK.
